ROTARY PRINTING PRESS

Curtis S. Crafts, Oak Park, Ill., assignor to The Goss Printing Press Company, Chicago, Ill., a corporation of Illinois

Application November 28, 1944, Serial No. 565,449

2 Claims. (CL 101—216)

1

The present invention relates to new and useful improvements in high speed rotary printing presses.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings referred to herein and constituting a part hereof, illustrate one embodiment of the invention, and together with the description, serve to explain the principles of the invention.

Of the drawings.

Figure 1 is a schematic side elevation of a typical and illustrative embodiment of the invention, with the frame of the press omitted;

Figure 2 is a detailed sectional view taken on the line 2—2 of Figure 1;

Figure 3 is a detailed elevation, with certain parts broken away, of one of the gears used in the embodiment shown in Figure 1; and

Figure 4 is a fragmentary top plan view of the printing press shown in Figure 1.

The present invention has for its object the provision of a novel and improved high speed rotary printing press having an improved drive for the printing couple and the inking drums. A further object of the invention is the provision of an improved rotary printing press which can be driven at higher speeds than have heretofore been considered commercially practical. Still another object of the invention is the provision of a high speed rotary printing press having relatively heavy ink distributing drums which are driven independently of the printing cylinders and operate at a constant speed of rotation regardless of the rapid changes in speed to which the cylinders of the printing couple may be subject.

In accordance with the present invention, the plate and impression cylinders of a high speed rotary printing press are geared together to rotate at the same speed and the ink for the plates on the plate cylinder is supplied by means of ink drums transferring ink to rollers which contact with the plates on the plate cylinder. The cylinders of the printing couple are driven from a compound bevel spur gear receiving its power from a main driving shaft while the ink drums are independently driven by separate driving means to the plates on cylinder 12 or 13. The plate

2

means from the main drive shaft. Preferably, the drive from the main drive shaft to the cylinders of the printing couple includes a resilient gear in which the teeth are so mounted as to have considerable flexibility or resiliency with respect to the hub of the gear so that while the printing couple rotates at an average speed which is constant, it is permitted to have slight, rapid changes in speed to accommodate for the small accelerations and decelerations which occur in the normal running of the cylinders of the printing couple.

Heretofore it has been customary to drive the relatively heavy ink drums from the plate cylinder, and due to the relatively great inertia of these heavy drums when operating at high speed, breakage of gear teeth has been frequent due to the inability of the teeth to transmit the excessive loads imposed on them by the rapid, although small, accelerations and decelerations of the printing couple cylinders. By the present invention, independent driving means are provided by which the cylinders of the printing couple are driven in a simple manner, independently of the heavy ink distributing drums so that the variations in the speed of running of one does not affect the drive of the other.

It will be understood that the foregoing general description and the following detailed description as well are exemplary and explanatory of the invention but are not restrictive thereof.

Referring now in detail to the illustrative embodiment of the invention as shown in the accompanying drawings, Figure 1 shows a high speed rotary printing press corresponding in general to a unit-type of newspaper press. In this press there are provided the impression cylinders 10 and 11 which run in printing contact with their respective plate cylinders 12 and 13. The stereotype printing plates carried by the plate cylinders 12 and 13 receive ink from the form rollers 14 which roll in contact with the plates and receive ink from an ink distributing drum 15 which, if desired, may be vibrated for better ink distribution. Drum 15 is provided with a distributing roll 16, and the drum receives ink from the transfer rollers 17 which also run in contact with another heavy, preferably vibrated, ink distributing drum 18, and drum 18 may likewise be provided with its distributing roller 19. The drum 18 receives ink from an ink fountain roll 20 through a doctor roller 21 so that the ink is slowly fed from the fountain to the distributing drums where it is reduced to a thin film and evenly distributed and is finally applied by the rollers 14 to the plates on cylinder 12 or 13. The plate

cylinders 12 and 13 are adapted to print on a web of paper W which passes up between the cylinders 10 and 12 around cylinder 12 and thence between cylinders 11 and 13 so as to be printed on both its sides.

The various cylinders, drums and rollers are mounted in suitable framing of conventional construction shown partially in Figure 4, and more completely shown in my prior Patent 2,085,185.

Means are provided for driving the cylinders of the printing couples and for this purpose power is supplied from a suitable motor to a main drive shaft 30 which extends vertically upward and is provided with a beveled gear 31 meshing with beveled gear 32 of the compound spur gear 33. The compound spur gear 33 meshes with a spur gear 34 to drive plate cylinder 13 and with a spur gear 35 to drive impression cylinder 10 so that the cylinders 10 and 13 are driven at the same speed. At the other ends of cylinders 10 and 13, gears are provided by which impression cylinder 11 is driven from plate cylinder 13 and the plate cylinder 12 is driven from the impression cylinder 10. As shown in my prior patent, impression cylinder 10 and plate cylinder 12 are intergeared at their far side for rotation together by means of the gears 38 and 39, and gears 40 and 41 are provided on the shafts of cylinders 11 and 13 to drive impression cylinder 11 from the plate cylinder 13.

Preferably the drive from the main drive shaft 30 to the cylinders 10 and 13 is through the resilient gears 34 and 35, although in some instances standard forms of gears may be used. Figures 2 and 3 illustrate more in detail the resilient gears, and as there shown, each resilient gear comprises a hub member 44 keyed to the shaft so as to be rigidly fixed thereon. Surrounding the hub portion 44 is a gear ring 45 having the gear teeth 46 formed thereon. The hub portion 44 and ring portion 45 are drivingly and resiliently interconnected by means of a plurality of resilient members permitting slight circumferential movement of the gear teeth in either direction with respect to the gear hub 44. While various resilient means may be employed, these resilient means preferably comprise rubber balls which are fitted in registering sockets formed on the adjacent edges of the hub 44 and ring 45, the size of the balls being so related to the sockets that they are held compressed and in shear. The balls 47 are preferably mounted in pairs, and are retained within the sockets by means of the retaining rings 48 which are secured by screws 49 at the outer ends of the sockets. As the gear ring 45 is driven, the shearing load is applied to the balls 47 in one direction so long as driving power is being applied while any tendency of the hub 44 to run ahead of the ring 45 applies a shearing load to the balls 47 in the opposite direction.

Means are provided for driving the inking mechanism from the main drive shaft 30 and as illustrated the hypoid gears 50 drive a horizontal shaft 51 at a reduced speed and shaft 51 drives the inking mechanism at both sides of the press. Near each end, shaft 51 carries a worm 52 which meshes with a worm gear 53 to drive the fountain roller 20 at a slow speed, and beyond the worm 52 is mounted a bevel gear 54 meshing with a bevel gear 55, a compound gear 56 which drives gear 57 fixed to the heavy distributing drum 18 and also drives idler 58 which in turn drives gear 60 fixed to the distributing drum 50. Thus an independent drive is provided for the driven roll-

ers and drums of the ink system to drive the fountain roll at a slow speed, and the ink distributing drums 15 and 18 at a faster speed which, however, is preferably approximately the same surface speed as the plate cylinders 12 and 13.

Ordinarily the various transfer and distributing rollers 14, 16, 17, 19 and 21 are not driven except by frictional contact with their various cooperating drums.

10 During the operation of the press, and particularly when operating at high speeds in excess of 25,000 plate cylinder revolutions per hour, the plate and impression cylinders are continuously subjected to accelerating and decelerating forces 15 while rotating at a substantially constant average speed. The drive from the main drive shaft 30 through the compound gear 33 to the cylinder gears of the printing couple absorb a large part of these sudden, though minute, variations in 20 speed, particularly where the resilient gears 34 and 35 constitute the driving connection from the compound gear 33 to the cylinders of the printing couples. By providing an entirely independent drive from the main drive shaft 30 to the heavy 25 ink distributing drums 15 and 18, these drums are allowed to rotate at their normal, constant speed without placing any undue load on any of the gear teeth such as has heretofore been the case where these drums were driven from the 30 cylinders of the printing couples. In the latter case the teeth of the intermediate gear between the printing couple and the ink train fail periodically. Making this gear of resilient construction, or making the gear which drives it from the 35 printing couple of resilient construction, is not a complete solution of the problem.

The present invention eliminates entirely the intermediate gear which was the only member subject to failure in the old rigid construction. 40 By providing resilient gears 34 and 35 on the cylinders of the printing couple to receive the driving power therefrom from compound gear 33, and by providing a separate power takeoff from the main drive shaft to drive the ink train, not only is the ink train driven by an essentially smooth flow of power and the rotational inequalities of the printing couple damped at their source, but the rapid acceleration and deceleration of the couple, in order to affect the ink train 50 at all, must not only surmount the damping power of gears 34 and 35 but travel backwards through gears 33, 32, 31, main shaft 30, gears 50, shaft 51, and gears 54, 55 and 56. The torsional flexibility of these shafts and the backlash 55 in these numerous gears are thus combined with the damping qualities of resilient gears 34 and 35 to provide complete damping of the inherent irregularities in speed of rotation of the printing couple.

60 The invention in its broader aspects is not limited to the specific mechanisms shown and described but departures may be made therefrom within the scope of the accompanying claims, without departing from the principles of the invention and without sacrificing its chief advantages.

What I claim is:

1. In a high speed rotary printing press having a rotary printing couple including plate and impression cylinders, and ink distributing drums to rotate with the cylinders, the combination of driving means for the cylinders and drums including a main drive shaft, resilient means for driving the cylinders from the main drive shaft, 70 gearing interconnecting the cylinders for driving

one from the other and separate driving means for driving the ink distributing drums from the main drive shaft.

2. In a high speed rotary printing press the combination of a rotary printing couple including plate and impression cylinders, means for driving the cylinders including gears interconnecting the cylinders, a main vertical drive shaft and a resilient gear between the drive shaft and one of the cylinders, to drive the cylinders, an ink drum, a fountain roller and a horizontal shaft driven from the main shaft, worm gearing interconnecting the horizontal shaft and the fountain

roller and bevel gears between the horizontal shaft and drum.
